ATTORNEY.

UNITED STATES PATENT OFFICE.

GEORGE K. THOMPSON, OF MAPLEWOOD, NEW JERSEY, ASSIGNOR TO AMERICAN TELEPHONE AND TELEGRAPH COMPANY, A CORPORATION OF NEW YORK.

DESIGN FOR A TELEPHONE-RECEIVER HOLDER.

53,093.

Specification for Design.

Patented Mar. 11, 1919.

Application filed November 6, 1917. Serial No. 200,642. Term of patent 14 years.

To all whom it may concern:

Be it known that I, GEORGE K. THOMPSON, a citizen of the United States, residing at Maplewood, in the county of Essex and State of New Jersey, have invented a new, original, and ornamental Design for Telephone-Receiver Holders, of which the following is a specification, reference being made to the accompanying drawing, forming part thereof.

Figure 1 of the drawing represents a front perspective view of the receiver holder, while Fig. 2 is a similar view showing the rear of the holder. The holder consists of a flat body-portion (1) having the configuration shown in the drawing and provided at its periphery with a plurality of clips (2, 3 and 4) extending in a direc-

tion substantially at right angles to the plane of the body-portion. Each of the clips is curved, as shown in the drawing, the curved portion of the clips being slightly spaced from the body-portion of the holder. Adjacent one edge of the body-portion of the holder and near the clip (4) is a raised boss (5), in the center of which is an opening (6). A pair of lugs (7 and 8) are arranged, one at the edge of the body-portion and the other within its periphery, said lugs extending to the rear of the body at substantially right angles to the plane thereof.

I claim:

The ornamental design for a telephone receiver holder as shown and described.

GEORGE K. THOMPSON.
